LAMP

Walter von Nessen, New York, N. Y., assignor to
The Chase Companies, Incorporated, Water-
bury, Conn., a corporation

Application March 21, 1934, Serial No. 716,614

8 Claims. (Cl. 240—4.1)

This invention relates to improvements in lamps, and more particularly to make-up lamps. One object of this invention is to provide an improved lamp having a mirror which, when in one position, covers the top of the lamp, and when in another position, serves for make-up or other use.

Another object of this invention is to provide an improved lamp construction having the minimum number of easily-assembled parts.

Another object of this invention is to provide an improved lamp construction having a light-transmitting globe connected at its lower end to a base, and at its upper end to means hingedly supporting a mirror.

Another object of this invention is to provide an improved lamp construction having a light-transmitting globe as a single integral member provided with integral lugs at its bottom and top for respectively connecting to a base and to means hingedly carrying a mirror.

With the above and other objects in view, this invention includes the improved features, parts and combinations of parts disclosed in the following description, appended claims and accompanying drawing forming a part of this specification.

In the accompanying drawing, in which one way of carrying out the invention is shown for illustrative purposes:

Fig. 1 is a central, vertical, sectional view illustrating a lamp embodying the invention;

Fig. 2 is a top plan view of the lamp illustrated in Fig. 1;

Fig. 3 is a view similar to Fig. 1, of the upper portion thereof, with the mirror swung to open or mirror-using position;

Fig. 4 is a perspective view of the ring-member and shade;

Fig. 5 is a perspective view of the light-transmitting globe; and

Fig. 6 is a perspective view of the base.

Referring to the drawing, the lamp includes a base 10 having an electric lamp socket 11 attached thereto by means of the screw 12 and receiving electric current from a suitable source of supply such as the electric cable 13. The lamp socket 11 has a switch-operating member 14 and carries an electric bulb 15.

The base-member 10 has an annular flange 16 provided with inwardly-extending lugs 17 adapted to engage or interlock with corresponding lugs 18 arranged around the flange 19 on the lower end of a light-transmitting globe 20 when the latter is rotated in the locking direction. The light-transmitting globe 20 is preferably closed at its upper end by the portion 21 and has lugs 22 arranged around its upper end and adapted to engage or interlock with corresponding lugs 23 arranged around the inside of a ring-member 24

when the latter is rotated in the locking direction. Ring-member 24 hingedly carries at 25, a mirror 26 having a reflecting mirror-surface 27.

The handle 28 serves for swinging the mirror either to the prostrate closed position shown in Fig. 1 where it covers the upper end of the light-transmitting globe, or to the open mirror-using position shown in Fig. 3, in which position it is especially effective for make-up use or the like, the face being lighted up by light passing through both the side and top of the globe 20.

A shade 29 may be used, and if so, is connected to or formed integral with the ring-member 24. The light-transmitting globe 20 is preferably made as a single integral member formed with the top 21 and the lugs 22 and 18 integral therewith. The globe 20 may be formed of glass or other suitable light-transmitting material and, to avoid glare, may be made of what is known as "translucent" glass.

The invention may be carried out in other specific ways than that herein set forth without departing from the spirit and essential characteristics of the invention, and the present embodiment is therefore to be considered in all respects as illustrative and not restrictive, and all changes coming within the meaning and equivalency range of the appended claims are intended to be embraced therein.

I claim:

1. A make-up lamp including: a base; a light-transmitting globe having its lower end connected to said base; and a substantially-opaque combined top cover and mirror hingedly connected at the upper end of said light-transmitting globe and designed and adapted selectively to permit of being swung to closed position to close off the passage of light from the upper end of said globe and to open position to bring the mirror into usable position.

2. A portable make-up lamp including: a base; a light-transmitting globe having its lower end connected to said base; a supporting-member connected to the upper end of said light-transmitting globe; and a substantially-opaque combined top cover and mirror hingedly connected to said supporting-member and designed and adapted selectively to permit of being swung to closed position to close off the passage of light from the upper end of said globe and to open position to bring the mirror into usable position.

3. A make-up lamp including: a base; a light-transmitting globe having its lower end connected to said base, and having its upper end connected to a ring-member surrounding said upper end; and a substantially-opaque combined top cover and mirror hingedly connected to said ring-member and designed and adapted selectively to permit of being swung to prostrate position to close

said ring-member and to open position to bring the mirror into usable position.

4. A portable make-up lamp including: a base; a light-transmitting globe in the form of an inverted bottle with a closed, large upper end and having its lower end open and connected to said base; and a substantially-opaque combined top cover and mirror hingedly connected at the upper end of said light-transmitting globe and designed and adapted selectively to permit of being swung to closed position to close off the passage of light from the upper end of said globe and to open position to bring the mirror into usable position.
5. A lamp including: a base; a light-transmitting globe having its lower end connected to said base; and a combined top cover and mirror hingedly connected at the upper end of said light-transmitting globe; said globe being a single integral member formed with integral lugs at its upper and lower ends for respectively connecting the globe to cooperating parts on said combined top cover and mirror and said base.
6. A lamp including: a base; a light-transmitting globe having its lower end connected to said base, and having its upper end closed and connected to a ring-member surrounding said upper end; and a combined top cover and mirror hingedly connected to said ring-member and adapted se-

lectively to be swung to prostrate position to close said ring-member and to open position to bring the mirror into usable position.

7. A lamp including: a base; a light-transmitting globe having its lower end connected to said base, and having its upper end closed and connected to a ring-member surrounding said upper end; and a combined top cover and mirror hingedly connected to said ring-member and adapted selectively to be swung to prostrate position to close said ring-member and to open position to bring the mirror into usable position; said globe being a single integral member formed with integral lugs at its upper and lower ends for respectively connecting the globe to cooperating parts on said combined top cover and mirror and said base.

8. A lamp including: a base; a light-transmitting globe having its lower end connected to said base, and having its upper end connected to a ring-member surrounding said upper end; and a combined top cover and mirror hingedly connected to said ring-member and adapted selectively to be swung to prostrate position to close said ring-member and to open position to bring the mirror into usable position; and a shade surrounding and connected to said ring-member.

WALTER VON NESSEN.
